UNITED STATES PATENT OFFICE

2,501,753

FISHHOOK

Leon L. Ayers, La Crosse, Wis.

Application December 26, 1946, Serial No. 718,280

1 Claim. (Cl. 43—43.2)

1

My invention consists in a new and useful improvement in fish hooks and is designed to produce a so-called weedless hook in which the conventional fish hook is provided with a guard member to prevent snagging of the hook in weeds or other subaqueous obstructions. This member comprises a loop engaged on the barb of the hook, a bead on which the tip of the hook is supported, and resilient means mounted on the hook's shank for properly positioning the bead to effect the desired result, viz. guarding the hook against engagement with the obstructions. The particularly novel and useful features of my device are the form and functioning of the bead and the character and operation of the resilient positioning means.

While I have illustrated in the drawing filed herewith and have hereinafter fully described one specific embodiment of my invention, it is to be distinctly understood that I do not consider my invention to be limited to said specific embodiment but refer for its scope to the claim appended hereto.

In the drawing:

Fig. 1 is a side elevation of the device.

Fig. 2 is a top plan.

Fig. 3 is an enlarged vertical section on the line 3—3 of Fig. 2.

Fig. 4 is an end elevation of the bead.

As illustrated in the drawing, the fish hook has a shank 1 formed at one end into a ring 2 for attaching the hook to the fishing line, and at its other end in a semi-circular bend 3 on the end of which is the point 4 having a divergent, slightly concave, inner face 5 extending rearwardly from the tip 6 of the point 4 to form the barb 7. A loop 8 of resilient wire has its ends suitably attached by wrapping 9 to the shank 1 and projects through ring 2 normal to shank 1. Passed through the bight 10 of loop 8 there is an elastic element 11, such as a continuous band of rubber or other suitable elastic material, having its bight 12 engaged in bight 10 of loop 8. Bight 13 at the other end of element 11 receives therein the end of loop 14 which is engaged on barb 7. A bead 15 is mounted on element 11 which is passed through a central, longitudinal bore 16 in bead 15. Bead 15 has square,

2

end faces 17 and 18 normal to the axis of bore 16 and four tapering sides 19 each having four faces 19—a, 19—b, 19—c and 19—d. As shown in Fig. 3, the longitudinal cross-section of bead 15 describes a decagon. The parts are so related that the spring loop 8 puts the elastic element 11 under tension when the loop 14 is engaged on the barb 7 and bead 15 is so disposed that the point 4 bears on bead 15, its face 5 passing over one of the faces 19—a and its tip 6 resting on the adjacent face 19—b (Fig. 3).

It is obvious that, when the parts are so disposed, the upper surface of the bead 15 against which the tip 6 fits snugly, due to the tension exerted by member 11 and loop 8, protects the hook to prevent its engagement with any obstruction, since the zenith of the bead is slightly superior to the tip 6. Due to the resiliency of element 11, the bead 15 is depressible to expose the point 6 of the hook when the fish seeks the baited hook, or is lured by the bead 15 which is composed of suitable highly colored, reflecting material, or transparent material, such as colored glass or other suitable composition. It will be noted (Fig. 1) that the loop 8 is adjustable (as indicated in broken lines) so as to compensate for stretching of element 11 by continued use, to maintain proper tension on bead 15.

Having described my invention, what I claim is:

In a fish hook, the combination of a conventional fish hook having a shank, tip and barb; and a lure comprising a body composed of highly-colored material resiliently mounted on said shank and said barb and engaging the inner side of said tip and projecting slightly past the end of said tip.

LEON L. AYERS.
